CLAIM

The ornamental design for a reversible belt buckle, substantially as shown and described.

DESCRIPTION

FIG. 1 is a frontal perspective view of a reversible belt buckle showing my new design;

FIG. 2 is a rear view thereof;

FIG. 3 is a front plan view thereof;

FIG. 4 is a right side view thereof; the left side being identical and opposite-hand; and,

FIG. 5 is a bottom side view thereof, the top side being identical and inverted.
